UNITED STATES PATENT OFFICE

HERMANN SCHULER, OF DUSSELDORF, GERMANY, ASSIGNOR TO RHEINISCHE METALLWAAREN- UND MASCHINENFABRIK, OF DUSSELDORF-DERENDRÖF, GERMANY, A CORPORATION OF GERMANY

FUSE-SETTING MACHINE

Application filed June 14, 1929, Serial No. 370,864, and in Germany September 1, 1927.

My invention relates to a fuse setting machine comprising two setting bodies adapted to be turned relatively to one another. The object of the invention is both to continuously impart to the setting bodies, by a peculiar arrangement and construction of their driving means, the required adjustment of the burning time in accordance with the dates of the aim (distance and level of the aim) and to obtain very rapid setting of the projectile fuses by an automatic operation of the machine.

My invention further provides means for enabling the fuse setting machine to simultaneously take up a plurality of projectiles and for setting them independently of one another.

In order that my invention can be more readily understood, an embodiment of the same is illustrated by way of example in the accompanying drawing in which

Figure 1 is a top view of my improved fuse setting machine,

Figure 2 is a sectional view thereof showing two vertical sections 90 degrees apart from one another, through two neighboring setting cups one of which is at rest while a projectile has been put into the other.

Figure 3 is a section through the lower portion of a setting cup on enlarged scale, shortly before the termination of the fuse setting operation.

Figure 4 is a similar section through a setting cup shortly after the termination of a fuse setting operation, with the driving means still thrown in.

Figure 5 shows by a similar section the cup in position of rest after the driving means has been uncoupled.

Figures 6 and 7 are sections on lines 1-1 and 2-2, respectively, of Figure 2, and

Figure 8 is a section on line 3-3 of Figure 5.

The fuse setting machine illustrated is fitted with two setting cups so that two projectiles can be set therein simultaneously. The cups consist of the cup-shaped upper setting bodies A having a spring-actuated setting bolt a, and of the coaxially arranged lower setting bodies B. The bodies A and

B are mounted for rotation in the casing C, the two cups being arranged like planet wheels about the central sun wheels D and E that drive them. The upper setting body A is in mesh with the sun wheel D by a toothed rim a₁, the sun wheel being turned e. g. by means of a hand drive h, Figure 1. When turned, this drive h at the same time displaces the pointer Z₁ of a following-the-pointer apparatus Z the counter mark Z₂ of which is displaced from a place remote from the setting machine, e. g. an observing station, in accordance with the respective dates of the aim. The pointer Z₁ is permanently caused by the drive h to register with the mark Z₂, whereby the two upper setting bodies A have imparted to them the angular position relatively to the two lower bodies B required for the determination of the bursting point to be obtained.

The lower setting body b which may be supported by ball bearings b₀ carries above its spring-actuated setting bolt b a supporting ring b₁ for the projectile. In the middle portion b₂ of body B is arranged a thrust piston b₃ the rod b₄ of which is guided in a hollow tap or sleeve c of the cup casing C and abuts on a spring f. The tap c further forms a bearing for the hub b₅ of body B.

When a projectile is put into cup B the point of the projectile comes to rest on the spring-actuated thrust piston b₃ and urges it downward by gravity. When this takes place a hook b₆ entrains a safety ring S by an arm s. This hook b₆ is connected to the piston b₃ and can swing about a pin b₇. It is under the action of a spring f₁ and passes through a slot b₈ of body B. The safety ring S is thereby shifted downward against the action of its supporting springs f₂ and releases the setting bolts a and b which till now were locked in the engaging position, so that they can give way as soon as they are urged outward by the projectile, unless the grooves of the projectile happen to be opposite them, so that they can enter these grooves.

The safety ring S is shiftably and rotatably mounted in the cylindrical cup casing C and is guided by a downward projection

*s*₁ in a corresponding recess *b*₁₁ of the lower setting body *B*, so that it takes part in the rotation of the latter. After introduction of a projectile ring *S* first perseveres in depressed position, as the outwardly shifted setting bolts *a*, *b* prevent its upward motion as long as they have not entered the grooves of the projectile. The hook *b*₈ releases ring *S* by its foot *b*₉ abutting on a stop *b*₁₀ after piston *b*₃ has reached its lowermost position.

10 The rotation, required to set the fuse setting ring, of the lower setting body *B* takes place by body *B* temporarily being coupled with a rotary member *g* the toothed rim *g*₁ of which is permanently in mesh with the sun wheel *E* which in its turn is permanently turned by a hand or power drive *m*, this coupled state being maintained during the setting operation. The coupling action is established by a coupling disk *k* adapted to engage by a toothed rim teeth *g*₂ of the rotary member *g* and to be lifted again out of these teeth by a slight rotation of the hub *b*₅ of body *B* which hub possesses high angle screw threads *b*₁₂. This rotation of the coupling disk *k* is effected by the rotary member *g* after body *B* has been stopped and is at rest, against the action of the spring *f*₃ arranged in body *B* and tending to provoke coupling.

15 By this rotation spring *f*₃ is tensioned through the intermediary of an arm *k*₁ of the coupling disk *k* which arm projects upward through a recess of the bottom *b*₁₃ of body *B*.

20 The coupling disk is thus resiliently rotatably connected to body *B* by spring *f*₃ and arm *k*₁. It can turn relatively to setting body *B* only by the amount allowed by the play of spring *f*₃ and in so doing it rises on the high angle threads *b*₁₂ whereby it is disengaged together with body *B* from the teeth *g*₂. As the spring *f*₃ acts in coupling direction, the coupling disk must be locked in uncoupled position when a rotation of body *B* should not take place.

25 The setting body *B* is arrested in known manner in dependence on the position of safety ring *S*. When the latter is in depressed position after introduction of a projectile, it is held first by the setting bolts *a* and *b* which are in depressed position. On the flange *d*₁ of a sleeve *d* which is non-rotatably but under the action of a spring *f*₄ axially shiftably mounted on the hollow tap *c* of casing *C* is arranged an arresting nose *d*₂. This nose can enter an arresting notch *b*₁₄ of the front face of the hub *b*₅ only after on the one hand a controlling ring *s*₃ which by means of projections *s*₂ is rigidly connected to safety ring *S* and abuts on the surface *d*₁ of sleeve *d*, is shifted upward by the springs *f*₂ together with ring *S*, after the bolts *a*, *b* have entered the respective grooves of the projectile, which ring *s*₃ thereby permits upward motion of sleeve *d*,

30 and, on the other hand, when the arresting notch *d*₁₄ that revolves with the bolt *b*, after the fuse has been set comes to lie above the arresting nose *d*₂ which is at rest. When the latter enters notch *b*₁₄ and setting body *B* thereby comes to rest with bolt *b* and high angle threads *b*₁₂, then the rotary member *g* still entrains for a short distance the coupling disk *k* against the action of spring *f*₃. The coupling disk *k* rises on the high angle threads *b*₁₂ and uncouples itself and there-with the setting body *B* from the rotary member *g* that continues revolving. Then the safety nose *i*₂ provided on the flange *i*₁ of sleeve *i* is under a safety notch *k*₂ of the hub of coupling disk *k* and enters this notch under the action of spring *f*₅ by sleeve *i* shifting, which sleeve may glide but not revolve on sleeve *d*. Owing to the flange *d*₁ of sleeve *d* covering flange *i*₁ of sleeve *i*, through which flange *d*₁ projects the safety nose *i*₂, sleeve *i* can rise only after sleeve *d* has been raised. When both noses *i*₂ and *d*₂ have entered the notches *k*₂ and *b*₁₄, respectively, then the flanges *d*₁ and *i*₁ abut on each other.

35 The described fuse setting machine operates in the following manner.

40 During the gun is firing, the rotary body *g* is permanently held in rotation in one direction by means of the hand drive *m* through sun wheel *E* and gear *g*₁. The setting body *A* with the bolt *a* has imparted to it by means of the drive *h* after the indications of the following pointer *Z* the rotary position required to set the fuse. Both setting bodies therefore are first at rest. The lower setting body *B* with bolt *b* is locked against rotation by the arresting nose *d*₂ engaging notch *b*₁₄. Coupling disk *k* is secured by nose *i*₂ engaging notch *k*₂. Now by introducing a projectile in the setting cup onto the supporting ring *b*₁ piston *b*₃ and therewith safety ring *S* and controlling ring *s*₃ are urged downward, the springs *f*₁ and *f*₂ being tensioned. This downward shifting motion is taken part in by the sleeves *d* and *i* with their noses *d*₂ and *i*₂, while springs *f*₄ and *f*₅ are tensioned, so that setting body *B* and coupling disk *k* are released by the noses *d*₂ and *i*₂, respectively. Owing to spring *f*₃ relaxing coupling disk *k* lowers on the high angle threads *b*₁₂ and couples the setting body *B* with member *g* that is revolving. Body *B* is thus set in rotation, entrains the projectile and turns it relatively to setting body *B* until bolt *a* of the latter enters the respective groove of the projectile and stops the latter. Now setting body *B* with bolt *b* shifts relatively to the projectile until bolt *b* enters the groove of the setting ring of the fuse. When this has taken place, at once safety ring *S* is raised above the bolts under the action of springs *f*₂, secures these bolts against backward motion

and, by the controlling ring s_3 being raised also, the arresting nose d_2 is enabled to enter notch b_{14} . In this instant begins the displacement of the setting ring of the fuse by bolt b . This displacement comes to end as soon as notch b_{14} comes to lie above the arresting nose d_2 which is at rest, and the latter enters notch b_{14} under the action of springs f_4 due to sleeve d raising. The setting body B then comes to rest, coupling disk k ascends on the high angle threads, is disengaged from member g and is secured in uncoupled position by nose i_2 entering notch k_2 . Whatever may be the mutual position of the bolts and their position relatively to the grooves of the projectile when a projectile is introduced, the setting of the setting ring of the fuse will always be terminated after at most two revolutions of setting body B. When the set projectile is lifted, piston b_3 rises under the action of spring f and is followed by the hook b_8 which locks ring S by engaging projection s of the latter.

In this manner the normal position of rest of the machine is reached automatically after the setting operation has been terminated. Each setting cup operates independently of the other, although actuated by the same drive. Therefore projectiles can be set in uninterrupted sequence simultaneously or after one another in both setting cups. Each cup sets its projectile independently of the operation of the other cups. To adjust the bolts of one or more setting cups actuated by one and the same drive the possibility of displacing the lower setting body B relatively to the upper body A is given in each setting cup. To this end the hollow tap c on which sleeve d is mounted which in position of rest is coupled in rotary direction with body B by nose d_2 , is mounted for rotation on the bottom c_1 of the cup and can be fixed by a nut c_2 . Tap c forms further the abutment for the springs f_4 and f_5 that partake in this eventual adjusting rotation.

To indicate to the crew the termination of a fuse setting operation, a light signal known in itself is provided on the machine. To this end sleeve d when rising after the setting operation has been terminated, releases an electric contact piece r which was depressed by pins t , which contact piece under the action of a spring f_6 meets a contact piece r_1 and closes the circuit including an incandescent lamp r_2 . When a projectile is introduced, sleeve d depresses the pins t and thereby breaks the contact so that lamp r_2 goes out.

What I claim and desire to secure by Letters Patent, is:—

1. A fuse setting machine for projectiles comprising upper and lower setting bodies adapted to rotate relative to one another,

said lower body being adapted to operate the setting ring of a projectile fuse; drive means for said lower body; coupling means therefore controlled by the introduction of a projectile; the upper setting body adapted by its position to determine the burning time of the fuse, and drive means for said body, said drive means being set in accordance with the range and level of the aim.

2. A fuse setting machine for projectiles comprising upper and lower setting bodies adapted to rotate relative to one another, said lower body being adapted to operate the setting ring of a projectile fuse; a projectile supporting ring in said lower body; a casing in which said body is rigidly mounted axially; drive means for said lower body; coupling means between said body and the drive means; and a movable actuating member for controlling said coupling means upon the introduction of a projectile into said lower body.

3. A machine according to claim 2, in which the coupling means comprises a disc having internal high pitched threads; a hub connection in said lower body having threaded engagement with said disc; and spring means operative with said coupling means upon introduction of a projectile into said body to couple the latter with said drive means, and operative to uncouple said body from said driving means after termination of the setting operation.

4. A machine according to claim 2, which includes setting bolts in the upper and lower setting bodies; a safety ring in the casing of the lower body adapted to be entrained through the action of the movable actuating member upon the introduction of the projectile to lock said bolts in engaging position therewith; independent locking means for the lower setting body and means operative with the safety ring to disengage the latter and thereby release the locking means of said body; and means operatively associated with the coupling means to prevent engagement of the locking means for the setting body until the setting bolts engage the projectile.

5. A fuse setting machine for projectiles comprising a plurality of upper and lower setting bodies, said bodies being adapted to rotate relative to one another, each of said lower bodies being adapted to operate the setting ring of a projectile fuse; setting cups in said upper bodies and common driving means for said cups; and means for coupling and uncoupling said driving means to set the fuses individually and independently of one another to permit the setting operation to take place in each setting cup independently of the others.

6. A fuse setting machine for projectiles comprising upper and lower setting bodies adapted to rotate relative to one another,

each of said lower bodies being adapted to operate the setting ring of a projectile fuse; setting cups in said upper bodies and a casing for each of said cups; drive means for each lower body; coupling means between said body and the drive means, comprising a threaded disc; a hub connection in said lower body having threaded engagement with said disc; fixed stops on the hub connection to limit the rotation of the setting bodies after termination of the setting operation, said stops being arranged to be displaced individually in the cup casing to adjust and re-adjust them.

15 In testimony whereof I have affixed my signature.

HERMANN SCHULER.
